MOVING PICTURE SCREEN

Application filed December 5, 1930. Serial No. 500,172.

In the common practice in talking motion picture arrangements, some of the sound reproducers are located to the rear of the movie screen. This necessitates that the screen be of such material that the sound may be transmitted therethrough with substantially no diminution of intensity. In the reproduction of heavy screens for use out-of-doors as, for instance, on shipboard where heavy wind pressures are to be dealt with, it is necessary that the screen be made in a substantial manner not only to prevent shimmering of the screen in breezes, but to prevent actual tearing of the screen under wind pressure, etc. This militates against providing a screen sufficiently thin to transmit the sound.

It is the object of the present invention to provide a screen so constructed so that it will not only properly transmit the sound from the sound reproducing apparatus located there behind, but will be of a durable and substantial character, and not subject to ripple in the wind.

A further object of this invention is to provide a new and improved talking motion picture screen.

Another object of this invention is to provide a new and improved talking motion picture screen wherein the sound is adapted to be transmitted therethrough substantially undiminished in volume.

A still further object of this invention is to provide a motion picture screen which shall be durable and may be readily folded for storage, etc.

These and further objects of our invention will become apparent from the following specification taken in connection with the appended drawing.

In accomplishing our invention a relatively thin screen material of the usual type having small holes for the transmission of sound made therethrough is utilized, and is backed up by a series of reinforcing strips forming a supporting network which will interfere only slightly with the transmission of the sound through the screen, and yet may be stretched tightly to thoroughly support the surface fabric.

Having thus briefly described our inven-

tion, attention is invited to the accompanying drawing in which;

Fig. 1 is an enlarged view of a portion of the movie screen constructed in accordance with our invention;

Fig. 2 is a general view of the movie screen constructed in accordance with our invention;

Fig. 3 is a cross-section of one form of our movie screen as taken along line 3—3 of Fig. 1;

Fig. 4 is a cross-section of one form of our movie screen as taken along line 4—4 of Fig. 1;

Fig. 5 is a cross-section of one form of our movie screen; and,

Fig. 6 is a cross-section of an alternative form of our movie screen.

Attention is now invited more particularly to the drawing in which the movie screen S is shown as composed of a surface material 11 preferably of relatively thin, high quality, closely woven, substantial cotton fabric. This screen material is sufficiently heavy to prevent any shadow or unequal illumination due to the effect of the framework or skeleton to be described hereinafter. The surface fabric 11 is perforated with a plurality of holes 13 of a dimension of preferably $\frac{1}{2}$ nd of an inch, and having a minimum group of about 60 to the square inch.

Sewn to the back of the surface material 11 is a skeleton or framework composed of horizontal and vertical strips 15 and 17 respectively. The horizontal strips are preferably sewn to the screen material first, and the vertical strips are sewn thereover as shown more particularly in Fig. 5. However, if desired, the spaces between the horizontal strip 15 may be filled in with a series of filler strips 19, as shown more particularly in Fig.

6. The skeleton or framework may be made of cotton duck material, such as number 6 cotton duck, or an equivalent braid may be used. In the event that cotton duck material is used, the strips are made up in double thicknesses as shown more particularly in Figs. 3 and 4, the strips being doubled along both marginal portions and the joint being in the middle thereof. The strip material

is used, the strips are made up in double thicknesses as shown more particularly in Figs. 3 and 4, the strips being doubled along both marginal portions and the joint being in the middle thereof. The strip material

is used, the strips are made up in double thicknesses as shown more particularly in Figs. 3 and 4, the strips being doubled along both marginal portions and the joint being in the middle thereof. The strip material

is used, the strips are made up in double thicknesses as shown more particularly in Figs. 3 and 4, the strips being doubled along both marginal portions and the joint being in the middle thereof. The strip material

another suitable dark color to prevent its showing through the surface material. The dyed or other colored material used should preferably be of a fast character to prevent 5 fading or running under any conditions of wind or weather.

Stretched around the entire outside of the screen is an outside border 21 of heavy cotton duck overlapping the skeleton members 10 and sewn thereto. In this border 21 are provided the usual grommets 23 for the purpose of fastening the screen to its frame. The metal grommets 23 utilized should be of such material as to be non-corrosive under different 15 atmospheric conditions.

In sewing the strips to the picture fabric, and also in sewing the border material 21 to the screen, care must be taken to prevent grouping of stitching from forming a 20 pattern.

Having thus described our invention, attention is invited to the fact that various modifications may be made therein, and that we are, therefore, not to be limited to the 25 specific embodiment shown and described for the purpose of illustration only, but by the actual scope of our invention as set forth and determined in the appended claims.

We claim:

30 1. A talking motion picture screen comprising a thin surface material, perforated for the transmission of sound therethrough, spaced reinforcing strips sewn horizontally on the back of said material, spaced filler 35 strips sewn vertically between the said horizontal strips, vertical reinforcing strips superposed on said horizontal strips and over said vertical filler strips, a border material attached to said screen and overlapping the 40 ends of said vertical and horizontal strips, and metallic grommets in said border material for permitting the rigging of said screen.

2. A talking motion picture screen comprising a thin surface material perforated 45 for the transmission of sound therethrough, spaced reinforcing strips sewn horizontally on the back of said material, spaced vertical strips sewn over said horizontal strips, a border material sewn around said screen and 50 overlapping the ends of said vertical and horizontal strips, and metallic grommets in said border material for permitting the rigging of said screen.

3. A talking motion picture screen comprising a thin surface material, perforated 55 for the transmission of sound therethrough, spaced reinforcing strips attached horizontally on the back of said material, spaced vertical strips attached to said material over 60 said horizontal strips, and a border material attached around the edge of said screen and overlapping the ends of said vertical and horizontal strips.

4. A talking motion picture screen comprising a thin sound-transmitting surface

material, spaced reinforcing strips sewn horizontally on the back of said material, spaced vertical strips sewn over said horizontal strips, a border material sewn around said screen overlapping the ends of said vertical and horizontal strips, and metallic grommets in said border material for permitting the rigging of said screen.

JOHN L. CASS.

BARTON KREUZER.
